UNITED STATES PATENT OFFICE.

JACOB R. SCOTT, OF BOSTON, MASSACHUSETTS, ASSIGNOR TO UNITED SHOE MACHINERY COMPANY, OF PATERSON, NEW JERSEY, A CORPORATION OF NEW JERSEY.

LEATHER-BUFFING MACHINE.

1,146,529.

Specification of Letters Patent. Patented July 13, 1915.

Application filed January 26, 1905, Serial No. 242,719. Renewed December 29, 1913. Serial No. 809,398.

To all whom it may concern:

Be it known that I, JACOB R. SCOTT, a citizen of the United States, residing at Boston, in the county of Suffolk and State 5 of Massachusetts, have invented certain new and useful Improvements in Leather-Buffing Machines; and I do hereby declare the following to be a full, clear, and exact description of the invention, such as will enable others skilled in the art to which it 10 pertains to make and use the same.

The present invention relates to leather buffing machines and particularly to machines for buffing articles of leather such as 15 box toe pieces, counter stiffeners, etc. The machine hereinafter specifically described as embodying the various features of the present invention in their preferred form is designed especially for operation upon box toe 20 pieces and counter stiffeners. The machine can, however, be used to operate satisfactorily upon other articles of leather, such, for instance, as belts, straps, welt strips and similar articles. While the invention is 25 particularly applicable to machines adapted for operation upon leather articles, similar to those above referred to, certain features of the invention are also applicable to other forms of leather buffing machines, such, for 30 instance, as machines for buffing the soles of boots and shoes.

The principal object of the present invention is to provide a machine for buffing leather articles of the character above referred to, having provision for bringing the 35 surface of the article to be buffed into proper position to be acted upon by the buffing tool and for supporting it in such position that the surface may be properly 40 finished by the tool without liability of the tool removing too much of the material at any point so as to mar or injure the article being operated upon.

Another object of the invention is to provide a machine for buffing articles of leather, comprising means whereby the action of the buffing tool may be prolonged on certain 45 portions of the article so that the desired amount of material may be removed from 50 these portions without a corresponding amount being removed from the other portions.

Other objects of the invention are to improve the construction of leather buffing machines and render them more efficient in 55 operation.

With the above objects in view the present invention contemplates the provision in a leather buffing machine of a yielding work support by which the work is supported in 60 contact with the buffing tool, and a presser arranged to press the work against the work support. By the provision of this yielding work support and presser the surface of the article which is to be buffed is brought into 65 the proper position to be acted upon by the buffing tool and is held in this position during the action of the tool thereon so that the desired amount of material is removed from 70 all portions of the surface regardless of 75 variations in the thickness of the article or irregularities in the surface which is being acted upon by the tool. In the illustrative machine the work support is constructed of yielding material such, for instance, as rubber, as in such case the material is displaced when the article is forced against the work support, allowing the article to be bent or distorted, if necessary, to bring the surface to be buffed accurately into the proper 80 position, and at the same time supporting all 85 portions of the article during the action of the buffing tool thereon. In buffing box toe pieces and counter stiffeners it is usually necessary to remove more material from the 90 edges than from the center of the blank in order to reduce the edges to the desired thickness. This result is secured by the use of a work support yielding material as the material which is displaced toward the edges 95 of the blanks tends to raise the edges and force them against the buffing tool. The buffing tool is preferably arranged to act upon the work in close proximity to the presser so that any liability of displacement 100 of the surface of the work after passing the presser and before reaching the buffing tool is avoided.

In buffing certain articles of leather it is desirable that the action of the buffing tool 100 be prolonged on certain portions of the article. Thus in buffing box toe pieces it is desirable to prolong the action of the buffing tool upon the upper portion of the blank in

- order to reduce this portion of the blank to a feather edge. In accordance with a feature of the present invention this result is accomplished by the provision of means for 5 imparting a varying feeding movement to the work while in contact with the tool. The feeding movement may vary in any desired manner, the action of the tool being prolonged either by intermitting the feeding movement or merely varying the speed 10 of the movement. In connection with the means above referred to for prolonging the action of the tool on certain portions of the work the present invention also contemplates the provision of means by which the work can be fed continuously at a uniform rate of speed when all portions of the surface of the work are to be acted upon uniformly. 15
- 20 In addition to the features of invention above referred to, the present invention also consists in certain devices and combinations of devices hereinafter described and claimed, the advantages of which will be obvious to 25 those skilled in the art.

The various features of the present invention will be clearly understood from the accompanying drawings, in which—

- Figure 1 is a view in side elevation of a 30 machine embodying the same in their preferred form. Fig. 2 is a view in front elevation of the machine. Fig. 3 is a view of the opposite side of the machine from that shown in Fig. 1. Fig. 4 is a central sectional 35 view taken on a vertical plane at right angles to the axes of the buffering roll and the work supporting and feeding roll. Fig. 5 is a sectional view taken on a vertical plane passing through and parallel with the axis 40 of the work supporting and feeding roll. Fig. 6 is a detail view in side elevation of a portion of the mechanism for imparting a varying feeding movement to the work, and Fig. 7 is a plan view of the parts illustrated 45 in Fig. 6.

Referring to the drawings, and particularly to Figs. 4 and 5, 1 indicates the work supporting and feeding roll, which as illustrated comprises a body portion of yielding 50 material in the form of a rubber sleeve 2, supported upon a metallic core 3. The core 3 is secured to a shaft 4 journaled in bearings in the side plates 5 of the machine frame, which rest upon a base plate 6 which in turn 55 rests upon the upper end of the side standards 7, forming the base of the machine frame. The side plates 5 and the base plate 6 are secured together and to the side standards 7 by bolts passing through the plates 6 60 and through flanges on the plates 5 and standards 7. The presser for forcing the articles to be operated upon against the work supporting and feeding roll is indicated at 8 and as illustrated consists of a metallic plate 65 rigidly secured to a plate 9 and extending

into close proximity to the surface of the work supporting and feeding roll, the plane of the flat presser plate 8 intersecting the feed roll or work supporting roll as shown in Fig. 4. The end of the presser plate, as 70 shown in this figure, is of reduced thickness and extends close to the bite of the rolls. The buffering tool is indicated at 10 in the form of a buffering roll which may be of any usual or suitable construction. The roll 75 illustrated consists of a rigid core 11 of wood or other suitable material, a yielding covering pad 12, of felt, and an abrasive covering 13 of sand-paper. The end of the presser plate 8 which contacts with the work 80 is reduced in thickness as is clearly shown in Fig. 4, and the buffering roll is arranged to act upon the work in close proximity to the end of the presser plate. The plate 9 to which the presser plate 8 is secured, is mounted upon the upper edges of the side plates 5 and extends over the work supporting and feeding roll and the buffering roll so as to form a casing to protect the hand 85 of the operator from injury by the rolls. An opening is provided in this plate through 90 which the articles to be operated upon are inserted.

Means hereinafter described are provided 95 for rotating the work supporting and feeding roll to feed the article and for rotating the buffering roll in the same direction, but at a much higher rate of speed. When the article is inserted through the opening in the plate 9 its leading end passes between 100 the presser plate 8 and the work supporting and feeding roll so that the article is clamped between the roll and the plate and is fed forward to the action of the buffering roll. Since the plate 8 extends into close proximity 105 to the surface of the work supporting and feeding roll the article is forced into the roll and its upper surface brought into a position to be acted upon by the buffering roll. The position of the upper surface of the 110 article is determined by the edge of the presser plate which in effect constitutes a forming plate for bending the article, if necessary, so as to bring the surface thereof into contact with the buffering roll. 115

The machine is designed particularly for 120 operation upon box toe pieces and as a box toe piece passes beneath the presser plate it is forced into the work supporting and feeding roll and bent so that its entire upper surface is brought into a position to be acted upon by the buffering roll. As the box toe piece is forced into the roll the yielding material of the roll is displaced and as a consequence the edges of the box toe piece are 125 forced upwardly slightly above the central portion and are held firmly against the periphery of the buffering roll. The proper finishing of the surface of the box toe piece near its edges is thus insured. 130

The work supporting and feeding roll acts as a die roll to receive the article being operated upon and allows the article to be bent into the required shape regardless of its size or thickness. Blanks varying considerably in size and thickness can therefore be operated upon in a satisfactory manner by the machine without changing the work supporting and feeding roll or adjusting the presser plate. To compensate for the wearing away of the surface of the work supporting and feeding roll, however, and to secure the proper amount of pressure upon articles of different thickness, means are provided for adjusting the presser plate 8 toward and from the periphery of the roll. To this end the plate 9 is adjustably secured to the side plates 5 by clamping screws 14 passing through elongated slots in the plate 20 and adjusting stop screws 15 are provided bearing against the upper and lower edges of the plate.

The buffing roll is secured to a shaft 16 journaled at its ends in blocks 17 mounted in the side plates 5. To enable the buffing roll to be adjusted toward and from the work supporting and feeding roll the blocks 17 are mounted in guideways in the side plates 5 and are adjustable toward and from the bearings for the shaft 4 to which the work supporting and feeding roll is secured, by means of adjusting screws 18. These adjusting screws have a screw threaded engagement with cap plates 19 secured to the side plates 5 and have a swiveled engagement with the blocks 17 at their inner ends. The screws 18 are locked in adjusted position by locking nuts 20.

The brush for cleaning the abrasive surface of the buffing roll is indicated at 21 as a rotary brush secured to a shaft 22 which is rotated by mechanism hereinafter described to cause the brush to rotate in the opposite direction to the buffing roll. In order that the brush may remain in engagement with the buffing roll when the buffing roll is adjusted, the shaft 22 is journaled in arms projecting downwardly from the blocks 17. The brush 21 is arranged beneath the buffing roll and at the rear of the work supporting and feeding roll so that as the article passes from between the buffing roll and the work supporting and feeding roll its buffed surface is brought into contact with the brush. The brush thus acts to clean both the abrasive surface of the buffing roll and the buffed surface of the article.

Leather buffing machines are usually provided with a suction apparatus for conveying away the fine dust produced by the action of the buffing roll. In the machine illustrated in the drawings a suction apparatus is provided comprising an exhaust fan 23 mounted in a suitable casing 24. 65 This casing is located at the rear of the buff-

ing roll and brush and the side adjacent to the buffing roll and brush is provided with openings through which the dust passes. To the upper portion of the fan casing a plate 25 is hinged which extends over the buffing roll and closes the space between the side plates 5. A perforated plate 26 extending between the side plates 5 below the brush and supported from the fan casing acts to prevent the passage of the buffed articles into the fan casing. The fan 23 is secured upon a shaft 27 which is journaled in bearings in the fan casing and driven at a high rate of speed by means of a belt from a power driven shaft 28 journaled in the lower portion of the side standards 7.

The mechanism for rotating the buffing roll and the brush at a high rate of speed in opposite directions consists of a pulley 29 secured to the buffing roll shaft, a pulley 30 on the power driven shaft 28, a belt passing over these pulleys, a pulley 31 upon the brush shaft, a corresponding pulley upon the fan shaft 27 and a belt passing over these pulleys.

For actuating the work supporting and feeding roll two mechanisms are provided, one acting to impart a continuous uniform feeding movement to the roll, and the other acting to impart a variable feeding movement to the roll. The continuous uniform feeding movement is imparted to the roll by means of a sprocket chain 32 passing over sprocket wheels 33 and 34 mounted respectively upon the shaft 4 of the work supporting and feeding roll and upon a shaft 35 journaled in the upper portion of the side standards 7. A continuous rotation is imparted to the shaft 35 from a power driven shaft 36 journaled in the upper portion of the side standards 7 through intermeshing gears 37 and 38. The sprocket wheel 33 is mounted to turn loosely upon the shaft 4 of the work supporting and feeding roll and can be clutched thereto by means of a friction nut 39 whenever it is desired to impart a continuous rotary movement to the roll.

The varying feeding movement is imparted to the work supporting and feeding roll by means of a pawl and ratchet mechanism actuated from a cam groove 40 cut in the face of the gear 37. This cam groove is engaged by a roll on a pivoted lever 41 the free end of which is connected by a link 42 to a pawl carrying arm 43 pivotally mounted upon a stud 44 projecting from one of the side plates 5. Also mounted upon this stud is a gear 45 which meshes with a gear 46 upon the shaft 4 of the work supporting and feeding roll. The pawl carried by the arm 43 is arranged to engage a ratchet wheel 47 secured to the gear 45 so that when the pawl is allowed to engage the teeth of the ratchet the gear 45 is intermittently actuated and an intermittent rotary movement is imparted

to the work supporting and feeding roll. The pawl for engaging the ratchet wheel 47 is indicated at 48 (see particularly Figs. 6 and 7), and consists of a spring pressed 5 plunger provided at its inner end with a tooth or projection adapted to engage the teeth of the ratchet wheel. The plunger is mounted in the arm so as to be capable of being rotated and is provided with a laterally projecting pin 49 arranged to engage either of two notches at the outer end of the arm 43. One of these notches is deeper than the other so that when the pin is in the deeper notch the tooth at the inner end of 10 the plunger is pressed against the ratchet wheel but when the pin is in the other groove the tooth at the inner end of the plunger is held out of engagement with the ratchet wheel and the arm 43 oscillates without actuating the wheel. The plunger is provided at its outer end with a knob by means of which the plunger can be withdrawn and turned through a quarter of a revolution whenever it is desired to throw the mechanism 15 for imparting a variable feeding movement to the work out of operation.

The object of the mechanism for imparting a variable feeding movement to the work supporting and feeding roll is to cause 20 the action of the buffing roll to be prolonged on certain portions of the article. In the machine illustrated in the drawings the cam groove 40 is so shaped that the work supporting and feeding roll is first rotated a 25 sufficient distance to bring the leading edge of the article into contact with the buffing roll. The roll then either remains stationary or moves very slowly for a short period and then the roll is moved to complete the 30 feeding of the article to the buffing roll and deliver it from between the rolls. In this manner a varying feeding movement is imparted to the article while in contact with the buffing roll and the action of the roll on 35 the leading edge of the article is prolonged. This manner of feeding the article is particularly advantageous when box toe pieces are operated upon as it is desirable that the upper portion of these articles be reduced to a thin edge. When it is not desired 40 to prolong the action of the buffing roll upon any portion of the article the pawl 48 can be withdrawn from engagement with the ratchet 47 and the sprocket wheel 33 45 clutched to the shaft 4 of the work supporting and feeding roll.

The shafts 28 and 36 are driven by belts 50 passing over belt pulleys 51 and 52 secured to the shafts. As a convenient means for 55 throwing the mechanism for actuating the work supporting and feeding roll out of operation the gear 38 is loosely mounted upon the shaft 36 and is clutched thereto by a suitable friction clutch operated by moving 60 the shaft 36 longitudinally. As illustrated,

the shaft 36 can be moved longitudinally to clutch the gear 38 to the shaft by means of a foot treadle 52 which is connected by a rod 53 to a sliding wedge 54 which is interposed between one of the bearings for the 70 shaft 36 and a block secured to the shaft. A spring pressed latch lever 55 serves to retain the treadle 52 in its depressed position and a spring 56 connected at one end to the treadle and at the other end to one of the 75 side standards 7, serves to raise the treadle when released by the latch lever. A similar arrangement is provided for clutching the belt pulleys to the shaft 28, comprising a 80 foot treadle 57, a wedge 58 and latch lever 59, the construction and operation of which parts will be obvious from an inspection of the drawings.

The operation of the machine has been fully indicated in the description given 85 above of the construction and arrangement of its various parts, and will be readily understood without a separate description thereof.

The nature and scope of the invention 90 having been indicated and a machine embodying the preferred form of the invention having been specifically described, what is claimed is:—

1. A leather buffering machine, having, in 95 combination, a buffering tool and means for holding the work in contact with the tool and for imparting a varying feeding movement to the work while in contact with the tool to prolong the action of the tool on certain portions of the work.

2. A leather buffering machine, having, in 100 combination, a buffering tool and means for holding the work in contact with the tool and for imparting automatically either a varying or a uniform continuous feeding movement to the work while in contact with the tool.

3. A leather buffering machine, having, in 105 combination, a work supporting and feeding roll, a presser to force the work against said roll, a buffering tool arranged to act upon the work in close proximity to the presser and mechanism for imparting a varying feeding movement to said roll to prolong the 110 action of the tool on certain portions of the work.

4. A leather buffering machine, having, in combination, a work supporting and feeding roll, a presser to force the work against said roll, a buffering tool arranged to act upon the work in close proximity to the presser, mechanism for imparting a varying feeding movement to said roll to prolong the 115 action of the tool on certain portions of the work, mechanism for imparting a continuous uniform feeding movement to said roll and means for rendering either of said mechanisms operative.

5. A leather buffering machine, having, in 120

combination, a buffing tool, means for holding the work in contact with the tool comprising a roll and mechanism for imparting automatically to the roll either a varying or 5 a uniform continuous feeding movement.

6. A leather buffing machine, having, in combination, a buffing tool, means for holding the work in contact with the tool and mechanism acting automatically to impart a 10 varying feeding movement to the work while in contact with the tool to prolong the action of the tool on certain portions of the work.

7. A leather buffing machine having, in combination, a buffing roll, a work supporting roll provided with a yielding surface, a flat presser plate having an end of reduced thickness extending close to the bite of said rolls, the plane of the plate intersecting the yielding roll, and means for rotating the 15

buffing roll at greater peripheral speed than 20 the supporting roll.

8. A leather buffing machine having, in combination, a buffing roll, a work supporting roll provided with a yielding surface, a flat presser plate having an end of reduced 25 thickness extending close to the bite of said rolls, the plane of the plate intersecting the yielding roll, means whereby said plate may be adjusted, and means for rotating the buffing roll at greater peripheral speed than the 30 supporting roll.

In testimony whereof I affix my signature, in presence of two witnesses.

JACOB R. SCOTT.

Witnesses:
